[57] CLAIM

The ornamental design for a combined towel dispenser and bracket, as shown and described.

DESCRIPTION

FIG. 1 is a top rear perspective view of a combined towel dispenser and bracket showing my new design. The dashed line showing of a mounting strap is for illustrative purposes only and forms no part of the claimed design;

FIG. 2 is an enlarged top left perspective view thereof; FIG. 3 is a top right perspective view thereof; and FIG. 4 is an enlarged fragmentary bottom perspective view of the closure portion, shown separately for clarity of illustration.

The undisclosed bottom portion is flat and unornamented.
